HOOKED RUG MAKING DEVICE

Foster K. Solliday, Grand Rapids, Mich.

Application May 27, 1935, Serial No. 23,566

12 Claims. (Cl. 112—80)

This invention relates to a device or machine for making hooked rugs. As constructed and disclosed herein, the device is hand operated, is provided with means for automatically feeding the same so as to uniformly space the loops made, is adapted to make use of different sizes of needles for different grades and sizes of yarn or other material fed through the needles, and has a number of adjustments for adjusting the feed, for spacing the rows of loops at different desired distances from each other and for adjusting and varying the distance that the loops are projected through the piece of material.

My invention is directed to the production of a device of the character described, and consists in many novel constructions and arrangements of parts for effectively attaining the ends stated, as well as many others not at this time enumerated, but which will appear as an understanding of the invention is had from the following description taken in connection with the accompanying drawings in which,

Fig. 1 is an elevation of the hooked rug making machine of my invention.

Fig. 2 is a side view thereof.

Fig. 3 is an elevation from the side opposite that shown in Fig. 1.

Fig. 4 is a like elevation showing the parts in a different position.

Fig. 5 is a diagrammatic view illustrating the manner in which the loops are spaced.

Fig. 6 is an elevation of an element of the structure which is turned to operate the needle and the feeding dog mechanism.

Fig. 7 is a section on the plane of line 7—7 of Fig. 6.

Fig. 8 is a fragmentary vertical section on the plane of line 8—8 of Fig. 1.

Fig. 9 is a fragmentary perspective view of the upper end of the bar, the lower end of which carries the feeding dog.

Fig. 10 is a transverse section on the plane of line 10—10 of Fig. 8.

Figs. 11 to 14, inclusive, are transverse sections on the planes of lines 11—11, 12—12, 13—13 and 14—14, respectively, of Fig. 3.

Fig. 15 is a fragmentary vertical section on the plane of line 15—15 of Fig. 3.

Fig. 16 is a fragmentary rear elevation of a needle of larger size, and

Fig. 17 is a transverse section through such needle, illustrating the type of guide used with the larger sized needles.

Like reference characters refer to like parts in the different figures of the drawings.

The construction.—A flat elongated bar 1 of metal has an offset portion 2 near its upper end and carries a handle 3 at its upper end. A disc 4 is mounted on a shaft 5 which is rotatably mounted on the bar 1 at the offset portion 2, the shaft being turned by a crank 6. The disc 4 is provided with an outwardly projecting cam 7 at one side.

The needle 8 is pointed at one end and is concavo-convex in cross section. Adjacent its pointed end the open side thereof is closed by a plate 8a permanently secured in place, the needle being open above and below such plate 8a. The upper end of the needle is formed into a cylinder, interiorly threaded, through which a threaded rod 9 passes, having its upper end turned at right angles to provide a shank 10 and terminating in a head 10a, made by cutting an angular groove around it near the end of the shank, (see Fig. 7).

The disc 4 is formed with a plurality of holes 11, disposed on a radius of the disc and spaced from each other, of a size such that the head 10a of the part 10 may pass therethrough. On the inner side of the disc 4, a thin sheet metal plate 12 is mounted to turn around the shaft 5 (Fig. 7) and having diametrically opposed finger engaging extensions 13. The sheet metal plate 12 is provided with a plurality of key hole slots 14, and has a detent 15 pressed therefrom diametrically opposite the slots 14 which releasably enters counter sunk holes in the disc 4 (Fig. 7). By turning the plate 12, springing the same away from the disc 4, to release the detent, the larger ends of the key hole slots 14 come into register with the holes 11 in the disc 4, and the head 10a on the shank 10 may be passed through disc 4 and plate 12. Then by turning the plate 12 back to its original position the needle is releasably locked to the disc 4, the groove part of shank 10 being received in the narrower portions of the key hole slots 14. The openings 11 on disc 4 are diametrically opposite the cam 7 thereon.

The needles extend alongside of the bar 1 and pass through suitable guides. For the smaller needles the guides are of U-shape, having a base 16 with spaced apart arms 17 which have openings to slidably pass the needle. For larger needles the closure of the open side at 8a is much shorter than for smaller needles and the guides 16 used in such case (Fig. 17) are of concavo-convex form, as indicated at 18, having inturned lips 19 which extend over the side edges of the larger needles 8. All guides, whether of the form shown in Fig. 15 or Figs. 16 and 17, are provided with 55

a cylindrical shank 20 grooved a short distance from its outer end at 21 to make a head similar to the head 10a previously described. At what may be termed the rear side of the bar 1 and 5 at the lower end portion a plate 22 is located and permanently secured as by spot welding. The plate 22 at its lower end portion is widened, as at 23, and at the upper edges of the sides of the widened portion formed with oppositely 10 extending ears 24. The bar 1 and the plate 22 have a plurality of openings 25 therethrough vertically spaced through any one of which the shank 20 of a needle guide may freely pass as shown in Fig. 15.

15 A locking plate 26 of sheet metal is located at the rear side of the plate 22, its lower end being vertically slotted to provide spaced apart fingers 27. The locking plate 26 is slidably mounted upon the plate 22 and held in place by 20 ears 28 (Fig. 11). This locking plate is lifted and the shank 20 of the guide for a needle inserted through a selected opening 25. The locking plate is then moved so that the edges of the fingers 27 are received in the groove 21 holding 25 the needle guide in place but permitting its rocking about the axis of the shaft 20.

The ears 24 previously described each carry a 30 guide sleeve 29. A wire rod is bent to make a lower slightly curved intermediate portion 30, with vertical sections 31 extending one from each end thereof for a distance, and then bent 35 horizontally at right angles to make terminal sections 32 which pass through the sleeves 29. This structure is adjustable back and forth in the sleeves and may be releasably locked in any 40 position to which adjusted. A leaf spring 33, having a headed screw 34 passing therethrough, has openings slightly elongated through which the terminal sections 32 pass. The screw passes 45 through the lower end portion of the plate 22 and threads into the bar 1 (Fig. 3). By operating the screw the spring 33 may be sprung outwardly at its ends so as to engage against and hold the sections 32 locked in any desired position.

An elongated bar 35 of thin metal is located 50 along one side of the bar 1 opposite the side where the plate 22 is secured. For purposes of description such side of the bar 1 will be termed the front side of the bar, the plate 22 being secured at the rear side. The thin metal bar 35 at its lower portion is widened and has a rectangular opening cut from the widened portion to provide spaced apart downwardly extending 55 sides 36 which are bent inwardly, first to lie along side the lower end portion of bar 1, and then at a lower point, bent still farther inwardly to bring the cross connecting piece 37, at the lower ends of the sides 36, against the front side of the 60 widened part 23 of the plate 22. Said widened portion 23 of plate 22 extends a short distance below the lower end of the bar 1 (Fig. 15). At the under edge of the cross connecting member 37 a pointed dog 38 is provided, best shown in 65 Figs. 3 and 15. Ears 39 are extended outwardly at opposite sides of and near the lower end of said sides 36 and bent around back of the widened section 23 (Fig. 1), thereby holding the lower part of the bar 35 in place but permitting it 70 a limited vertical sliding movement.

The upper end of the bar 35 has a rearwardly turned lip 40 (Figs. 2 and 9) which lies directly under the disk 4 and is engaged periodically by the cam 7 to move the bar 35 in a downward 75 direction. A short distance below the rearwardly

turned lip 40 a tongue 41 is struck from the bar rearwardly and at right angles to the bar. Also integrally therewith a wider head portion 42 is struck which is turned downwardly at right angles from the tongue 41 (Fig. 9). The material cut from the bar 35 to make the tongue 41 and its terminal head 42 leaves a T-shaped opening 43 in bar 35 (Fig. 4).

A vertical elongated slot 44 is cut lengthwise of the bar 1 and has horizontal branches 45 a short distance below its upper end permitting the passage of the head 42 therethrough and then an upward movement of the bar 35, the tongue 41 being slightly narrower than the slot 44. A light coiled compression spring 46 is 10 housed in slot 44 between the sides thereof, bearing at its upper end on the tongue 41 and at its lower end against the lower end of the slot. As shown in Fig. 1, the plate 22 covers a considerable portion of the lower end of slot 44 thereby retaining the spring in place while the head 42 holds the lower end of spring 46 in place.

Operation.—With a selected needle installed and with the shank 10 thereof connected with the disc 4, and the needle guided through the 25 arms 17 of the guide member, yarn 47 is threaded through the needle back of the plate 8a and out below the lower edge of said plate. The part 31 of the spacing gauge mechanism and the lower edge of the part 23 are brought against the fabric 48 through which the yarn is fed and looped. Turning the crank 6 causes a reciprocation of the needle with each rotation of the disc 4 and also reciprocation of the bar 35 with each of said 30 rotations. Assuming the parts to be in the position shown in Fig. 3 at the start of operations, the cam 7 is bearing upon the lip 40 at the upper 35 end of bar 35, forcing the pointed dog 38 into the fabric 48. With a continuation of rotation to the position shown in Fig. 4, the bar 35 has 40 been released and lifted by the spring 46 to disengage the dog 38, and the needle moved downwardly, piercing the fabric and carrying the yarn therethrough until the needle reaches its lowermost position diametrically opposite the position 45 shown in Fig. 3. Thereafter with a continuance of rotation of disc 4, the needle is withdrawn from the fabric and the yarn formed into a loop, a series of which are shown at 49, one of which is made with each rotation of the disc 4. The 50 loops are on the reverse side of the fabric and are connected by stitches 50 on the opposite side of the fabric.

The design of the machine is such that as the 55 needle in its upward movement leaves the fabric, cam 7 comes against the lip 40 on bar 35 and forces the dog 38 into the fabric. The needle movement is not a straight up and down movement but is a combination of a reciprocating movement with a swing from one side to 60 the other such that the point of the needle takes a path substantially like that indicated in broken lines at A in Fig. 3. The path of the needle after it has left the fabric and is moving over to re-engage the fabric is shown in Fig. 5, as moving 65 from the point B, where it leaves the fabric, to the point C where it again enters the fabric. This is the result of the swinging movement of the lower end of the needle which pivots about the axis of the shank 20. At the same time, the 70 dog 38 having engaged the fabric, the device as a whole is held against movement with respect to the fabric, whereby the needle moves over the fabric from the point of leaving the same at B to the next entrance point at C. (As in Fig. 5). 75

It is evident that by moving the shank 20 of the guide to different openings 25 the length of the feed may be increased or diminished and in this way the distance between loops varied and regulated.

It is further evident that by connecting the upper end of the needle at different openings 11 in the disc 4 the stroke of the needle may be varied as well as the distance that the point 10 of the needle will swing after it has left the fabric and before it again pierces the same. The threaded connection of the rod 9 with the needle permits adjustment of the length of the needle. The gauge for spacing the rows of stitches and 15 loops from each other, consisting of the wire member, having sections 31, 32 and 33, is positioned so as to ride alongside a row of stitches and thereby uniformly space the needle entrance through the fabric from the preceding rows of 20 stitches.

It will be noted that the position of the needle with respect to the remaining parts of the machine, when the needle is connected in operable position, presents the open lower end portion of 25 the needle and the open side of the needle above the plate 8a in a plane substantially parallel with the plane of the width of the supporting bar 1. That is, when the yarn is entered into the needle above the plate 8a and goes therefrom 30 through the opening at the lower end of the plate 8a, the plane of such opening is in substantially the same vertical plane as the row of stitches or loops produced.

Such a positioning of the needle permits operating the crank 6 in either direction which permits change of direction of the device as a whole, and also permits complete reversal of direction of movement of the machine over the fabric material 48 without changing the needle 40 or in any way adjusting or changing the mechanism. This is a very desirable and novel feature of the invention and one which has proven particularly practical.

The construction described, while of a relatively 45 simple character, is very easily operated and particularly practical. The wide range of adjustment and the ability to use different sizes of needles allow the use of one machine in making so-called hooked rugs from a wide variety of materials and 50 with spacing of the rows of loops or stitches and distance of projection of the loops also widely variable. The larger needles have the shorter closing plates 8a near their pointed ends to cut down the friction of the passage of the yarn or 55 other material through the needles which would be excessive in the larger needles using the larger yarns or other materials, if the lengths of plates 8a for the larger needles were similar to that shown in Figs. 3 and 4 which are needles of the smaller 60 size and through which smaller sizes of yarn or other material 47 pass. This necessitates the two constructions of guides described. However there is no difference whatsoever in performance or principle of operation.

65 The invention is defined in the appended claims and is to be considered comprehensive of all forms of structure coming within their scope.

I claim:

1. In a machine of the class described, a supporting bar, a needle mounted thereon for reciprocating and rocking movements, means for operating said needle to reciprocate and simultaneously rock the same, a second bar slidably mounted on the first bar and having a dog at its lower 75 end, means for moving said second bar to project

the dog downwardly at the time the needle is at its uppermost position, and a gauge adjustably mounted adjacent the lower end of said bar and adjustable toward and away therefrom, said gauge having a portion to engage with a row of 5 stitches or tufts previously produced.

2. In a device of the class described, a supporting bar, a disk having a cam at one side rotatably mounted on said bar, means to rotate the disk, a needle connected at one end with the disk, a guide 10 through which the needle passes mounted for rocking movement on said bar, a second bar mounted on and located against the first bar and having its upper end located to be engaged by the cam on said disk, said second bar at its lower 15 end having a pointed dog, and yielding means normally elevating the second bar to bear against the edge of said disk.

3. A construction containing the elements in 20 combination defined in claim 2, including means carried by said disk, and said disk having a plurality of openings, for the adjustable mounting and locking of the upper end of the needle to said disk, said bar adjacent its lower end having a 25 plurality of openings in any one of which the needle guide may be mounted for rocking movement, and a releasable locking means mounted on the bar for securing the needle guide in place.

4. In a machine of the class described, wherein 30 a supporting bar has a needle mounted for reciprocating and rocking movements thereon combined with a means for operating the needle, of a guide carried on and a short distance above the lower end of said supporting bar, a spacing gauge 35 formed of a single length of wire having a substantially horizontal lower portion, a vertical section turned upwardly from one end thereof, and a horizontal section turned from the upper end of said vertical section passing through said guide, 40 and means for releasably engaging said horizontal section for holding the gauge in any position to which adjusted.

5. In a construction of the class described, a supporting bar having an offset portion between 45 its ends and near its upper end, a handle at the upper end of the bar, a shaft mounted on the bar extending through said offset portion, a circular disk having a cam projection at one side secured to said shaft, a needle comprising a lower yarn 50 carrying member and an upper shank, means for detachably connecting said shank to the disk, and a needle guide mounted for rocking movements adjacent the lower end of the bar, said 55 guide engaging the needle and holding it in a plane substantially parallel to that of the bar but permitting reciprocatory movements of said needle as specified.

6. A construction containing the elements in 60 combination defined in claim 5, said needle guide comprising a member embracing the sides of the needle and extending around the same and having inturned lips engaging the edges of the needle, and a shank projecting from said member, said shank passing through an opening in the bar in 65 which it may have rocking movements, and a slideable lock mounted on the bar to detachably engage the end of the shank and hold the same in position while permitting rocking movement.

7. A needle for use in the machine of the class 70 described, comprising a sheet metal concavo-convex member having an open side and a pointed lower end, a plate closing the open side of the needle from a short distance above the lower 75

pointed end thereof upwardly for a distance, said sheet metal member at its upper end having an interiorly threaded tube, and a shank threaded into the upper end of the tube having the upper end terminal portion turned substantially at right angles.

8. In a machine of the class described having a vertical supporting bar, a needle mounted thereon and means to operate the needle, of two spaced sleeves mounted on and a short distance above the lower end of the bar, said sleeves being in a horizontal plane, a gauge member formed from a single length of material having an intermediate horizontal section, two spaced vertical sections extending from the ends of the horizontal section and terminal horizontal sections extending from the upper end of the vertical sections and passing through said sleeves, a leaf spring having slightly elongated horizontal openings therein through which said horizontal sections of the gauge member pass, and a screw passing through said leaf spring between its ends and threaded into the bar for the purpose described.

9. In a machine of the class described, a supporting bar, a needle guide adjustably mounted thereon toward the lower end of said supporting bar and adapted to be adjusted to a plurality of different positions at different distances above the lower end of the bar and releasably locked in any selected position, a needle slidably passing through said guide, manually operable means carried on said bar with which the upper end of the needle is connected for reciprocating the needle through said guide and rocking the same back and forth about the axis of the guide, a second bar slidably mounted on and lengthwise of the first bar having a pointed dog at its lower end, spring means normally lifting said second bar to raise said dog above the lower end of the supporting bar, and means operated by the aforementioned manually operable means for moving said second bar downwardly to bring the dog below the lower

end of the first bar and at a time when the needle is elevated to its upper position.

10. In a machine of the class described, a supporting bar, a needle mounted thereon for reciprocating and rocking movements, means for operating said needle to reciprocate and simultaneously rock the same, a second bar slidably mounted directly on the first bar and having a dog at its lower end, said second bar being independently movable with respect to the needle, and means for moving said second bar at a different rate of speed than that of the needle.

11. An apparatus for working upon a fabric comprising, a supporting member, a needle having an opening at its outer side and at its lower end through which yarn or like material passes, means for mounting the needle upon the supporting member whereby its point may move in a continuous closed path, means for moving the point of the needle in said path, means attached to the supporting member and contacting the fabric whereby the point of the needle is free from the said fabric during a predetermined portion of its travel, holding means spaced from the point of the needle adapted to engage the fabric to prevent movement of the supporting member and operating means adapted to operate the holding means during the time when the point of the needle is free from the said fabric, said operating means maintaining the holding means in a predetermined maximum degree of engagement whereby the device can be slightly tilted to withdraw the said holding means.

12. In a machine of the class described, a supporting bar, a needle mounted thereon for reciprocating and rocking movements, means for operating said needle to reciprocate and simultaneously rock the same, a second bar slidably mounted on the first bar and having a dog at its lower end, and cam means for moving said second bar at a different rate of speed than that of the needle.

FOSTER K. SOLLIDAY.
